UNITED STATES PATENT OFFICE.

LEWIS S. PHILLIPS, OF GENEVA, NEW YORK, ASSIGNOR, BY MESNE ASSIGNMENTS, TO PHILLIPS & CLARK STOVE CO., INC., OF GENEVA, NEW YORK, A CORPORATION OF NEW YORK.

STOVE.

1,288,981.

Specification of Letters Patent. Patented Dec. 24, 1918.

Application filed October 2, 1915, Serial No. 53,857. Renewed December 29, 1917. Serial No. 209,605.

To all whom it may concern:

Be it known that I, LEWIS S. PHILLIPS, a citizen of the United States, residing at Geneva, in the county of Ontario and State 5 of New York, have invented certain new and useful Improvements in Stoves, of which the following is a specification.

The object of this invention is to provide a new and improved type of stove in which 10 the oven may be heated either by coal or by gas or by both.

This and other objects of the invention will be fully illustrated in the drawings, described in the specification and pointed 15 out in the claims at the end thereof.

In the drawings,

Figure 1 is a perspective view of the stove partly broken away showing the oven and the arrangements for the heating thereof.

20 Fig. 2 is a vertical section taken on the line 2^x—2^x of Fig. 1, showing the left hand side of the oven.

Fig. 3 is a horizontal section taken on the line 3^x—3^x of Fig. 2.

25 In the drawings like reference numerals indicate like parts.

In the drawings reference numeral 1 indicates a stove in which is provided a grate 2 in which coal is burned in the ordinary 30 manner for heating the top of the stove and the oven. 3 indicates the top of the stove and 4 indicates the oven. The products of combustion from the grate pass through the horizontal flue 5 at the top of the oven, a 35 downward inclined flue 6 at the corner of the oven and a vertical flue 7 at the side of the oven and through a horizontal flue 8 at the bottom of the oven. From the horizontal flue 8 the products of combustion 40 pass rearwardly into the smoke pipe 9. This part of the stove is similar to that which is ordinarily used in coal ranges.

Below the lower left hand corner of the oven is placed a chamber 10 having the gas 45 burners 11 and 12 therein. This chamber is separated from the ash pit and grate or fire box by a wall 13. At the left of the oven is carried a plate 14 between which plate 14 and the wall 13 is formed the passage way 50 16 through which the products of combustion from the gas burners 11 and 12 pass

upwardly. At the front end of the plate 14 are formed the openings 15, 15, 15, through which a part of the products of combustion may pass around the side of the plate 14 55 into the oven 4.

As will be seen from Fig. 3, the sides of the plate 14 are curved to make contact with the wall 13. The plate 14 terminates short of the top of the oven 17 so as to provide an 60 opening at the top of the oven through which the products of combustion from the gas burners can enter the oven. The plate 14 is fastened to the wall 13 by the bolts 18. As shown in Fig. 1 the plate 14 and wall 65 13 are inclined to the left at the lower corner of the oven where they communicate with and form the chamber that contains the gas burners.

Through the opposite side of the oven at 70 the bottom is provided an opening 19 into the flue 7 through which the products of combustion from the burners emerge into the flue 7. A damper 20 is provided by which this opening may be closed when 75 gas is not being used and when the coal is being burned in the grate.

The front of the stove is closed by a plate 21 which carries the door of the oven. This plate is partly broken away so that the 80 structure of the oven may the more clearly appear. This plate also closes the end of the chamber containing the gas burners and the ends of the flues 5, 6, 7 and 8 and the inner margin of it substantially coincides with 85 the edge of the walls of the oven, coinciding with the edge of the straight upper portion of the wall 13.

As will be seen from Fig. 1, four plates on the top of the stove are ordinarily 90 heated from the grate, while four other plates are heated from gas burners which are placed thereunder, the flue 6 being curved downwardly under the third pair of plates to provide room between the flue and 95 the plates for the burners. This, however, is a well known feature in stove construction and constitutes no part of my invention.

The chamber 10 is provided with the openings 22 therein through which air can 100 enter from below the stove to support the combustion. The burners 11 and 12 are

fed with gas through the pipe 23 through suitable valve connections.

The plate 14 is placed at the side or end of the oven and is so constructed and placed that it will not interfere with the heating of the oven by the grate directly through the wall adjacent to the grate. For this purpose the plate 14 is provided with holes at the side which permit the circulation of air around the end of the plate and the plate stops short of the top of the oven so that air can pass over the top of the plate. When the oven is heated by coal alone, the heat of the side wall of the fire box will be communicated directly to the oven because of this circulation of air. Because of this arrangement this plate 14 does not interfere with the heating of the side or end of the oven by the grate.

20 The plate 14 also acts as a deflecting plate for the products of combustion of the gas burner and being without any openings therein near the burners it prevents any flames from the gas burner entering the oven proper and prevents the products of combustion of the burning gas from directly entering the oven at the bottom but allows the hot atmosphere to pass it at points that are beyond the reach of the flames. This 25 plate distributes the products of combustion from the gas burner so that they will not only heat the plate but will also enter the oven some distance above the bottom either around the end of the plate or over the 30 top of it heating the oven more especially from above and after the products of combustion from the gas pass the plate 14 they must traverse the whole length of the oven before they can reach the exhaust opening 35 19, which exhaust opening is proportioned in size to the opening through which the products of combustion enter the oven from the gas burners and pass into the vertical flue 7 and from thence into the bottom flue 40 8. This arrangement of the gas burner and deflecting plate leaves the bottom of the oven free from any obstruction due to the gas burner. It also causes the oven to be heated first from within and from above. And 45 thereafter when the products of combustion from either coal or gas pass through the flue 8 they are applied to the heating of the oven on the outside so that the oven is also heated from below directly through the one 50 bottom plate of the oven. In this way a good distribution of heat with a uniform heating of the oven is secured which will avoid an intense local heat or overheating in any place.

55 The heat is applied from a burner outside of the oven first directly to the interior of the oven and thereafter directly through the bottom of the oven and does not have to pass through some other plate forming a second bottom of the oven as well, which plate is

used in many stoves where the burner is placed in the bottom of the oven or where the burner is placed outside of the oven and the heat from it enters the oven at the bottom corner or corners of the oven. This 70 plate must usually be removed when the oven is heated by the burning of coal alone.

It will also be seen that in applicant's stove the products of combustion from coal and gas follow substantially parallel courses 75 through the stove and are kept separate from each other by the walls of the oven till they reach the damper 20 and thereafter they mix and follow one and the same course through the stove namely the flues 7, 8 and 80 9 to heat the oven bottom from beneath.

In applicant's stove the only change that must be made to adapt it to the several kinds of heating is the opening and closing of the damper 20. 85

I claim.

1. In a combined coal and gas range the combination of an oven capable of being heated by either coal or gas or both, said oven having a coal grate at one side thereof and a flue therefrom passing over the top, down the side and under the oven and up at the back of the oven, a gas combustion chamber located at the lower corner of the oven and under the coal grate and sealed 90 from the grate, a passageway leading up from said combustion chamber to the top of the oven and discharging the products of combustion at the top and side of the oven, an exhaust opening at the opposite 100 side of the oven near the bottom thereof through which the products of the gas combustion can pass directly into the downwardly extending portion of said flue passing down therethrough and through the 105 other flues and under the bottom of and up at the back of the oven.

2. In a combined coal and gas range the combination of an oven capable of being heated by either coal or gas or both, said 110 oven having a coal grate at one side thereof and a flue therefrom passing over the top, down the side and under the oven and up at the back of the oven, a gas combustion chamber located at the lower corner of the 115 oven and under the coal grate and sealed from the grate, a passage way leading up from said combustion chamber to the top of the oven and discharging the products of combustion at the top and side of the 120 oven, an exhaust opening at the opposite side of the oven near the bottom thereof through which the products of the gas combustion can pass directly into the downwardly extending portion of said flue passing down therethrough and through the other flues and under the bottom of and up at the back of the oven, a valve for closing 125 said exhaust opening.

3. A range having an oven therein with 130

- a coal grate on one side thereof with a flue therefrom passing over the top, down the side, under the bottom and up the back of the oven, a gas combustion chamber located 5 under the lower corner of the oven and under the coal grate and separated therefrom, said gas combustion chamber discharging its products of combustion directly into the oven, a plate for deflecting it to the top of 10 the oven, an exhaust opening on the opposite side of the oven for discharging the products of combustion directly into the downwardly extending portion of said flue.
4. In a combined coal and gas range the 15 combination of an oven having a coal grate and a gas combustion chamber on one side thereof separated from each other and located outside of said oven, a flue for the coal grate arranged over the top and down 20 the opposite side of the oven, the oven being connected with the gas combustion chamber to permit the products of combustion of the gas chamber to first heat one of the side walls of the oven and pass into 25 the upper part of the oven on one side thereof and thence across or through the oven itself and into said flue on the opposite side of the oven, near the bottom thereof, and through a common flue arranged under the 30 oven and up the back of the oven.
5. In a stove the combination of an oven, a gas burner and a coal grate for heating said oven, said burner and grate being separated from each other and being located 35 outside of the oven, means for separately conducting the products of combustion of the coal grate partway around the outside of the oven, means for conducting the products of combustion of the gas burner first 40 against one of the side walls of the oven and thence into the oven near the top on one side and thence to the bottom of the oven on the other side, means for combining the products of combustion outside of the oven 45 and passing them directly under the oven and up the back of the oven.
6. In a stove the combination of an oven, a gas burner and a coal grate for heating said oven, said burner and grate being separated from each other both being located 50 outside the oven and at one and the same side of the oven and both operating to first heat said side of the oven, means for heating said oven by the products of combustion of said grate and burner, said means permitting the heating of the oven either from the grate on the outside or the burner 55 partly on the inside and partly on the outside either separately or from both together 60 at one and the same time, the products of combustion of both the grate and burner coming directly into contact with the oven during the whole passage thereof through the stove.
- 65 7. In a stove the combination of an oven, a gas burner and a coal grate for heating said oven, said burner and grate being separated from each other and being located outside of the oven and at one and the same side of the oven and both operating to first heat said side of the oven, means for heating said oven by the products of combustion of both the grate and burner coming directly into contact with the oven during the whole passage thereof through the stove.
8. In a stove the combination of an oven, a gas burner and a coal grate for heating said oven, said burner and grate being separated from each other and being located outside of the oven and at one and the same side of the oven and both operating to first heat said side of the oven, means for heating said oven by the products of combustion of both the grate and burner, said means permitting the heating of the oven either from the grate on the outside or the burner partly on the inside and partly on the outside either separately or from both together, the products of combustion of both the grate and burner coming directly into contact with the oven during the whole passage thereof through the stove, and being kept separate from each other until they pass the top of the oven.
9. In a stove the combination of an oven, a gas burner and a coal grate for heating said oven, said burner and grate being separated from each other and being located outside of the oven and at one and the same side of the oven and both operating to first heat said side of the oven, means for heating said oven by the products of combustion of both the grate and burner, said means permitting the heating of the oven either from the grate on the outside or the burner partly on the inside and partly on the outside either separately or from both together, the products of combustion of both the grate and burner coming directly into contact with the oven during the whole passage thereof through the stove, said means preventing the products of combustion from the grate from entering the oven.
10. In a stove the combination of an oven, a gas burner and a coal grate for heating said oven, said burner and grate being separated from each other and being located outside of the oven and at one and the same side of the oven and both operating to first heat said side of the oven, means for heating said oven by the products of combustion of both the grate and burner, said means preventing the products of combustion from the grate from entering the oven.

each other while following substantially parallel courses and thereafter joining them for further application to the oven, said means preventing the products of combustion from the grate from entering the oven.

5 11. In a combined coal and gas range the combination of an oven having a coal grate and a gas combustion chamber located at one side thereof and outside of the oven, 10 a passageway communicating between the gas combustion chamber and the inside of the oven, a deflecting plate extending from below said passageway upwardly in said oven by which the products of combustion 15 of said gas combustion chamber are deflected toward the top of said oven, an exhaust opening on the opposite side of said oven through which the products of combustion escape from said oven after traveling the length of the oven.

20 12. In a combined coal and gas range the combination of an oven having a coal grate and a gas combustion chamber located at one side thereof and outside of the oven, 25 a passageway communicating between the gas combustion chamber and the inside of the oven, a deflecting plate extending from below said passageway upwardly in said oven by which the products of combustion 30 of said gas combustion chamber are deflected toward the top of said oven, an exhaust opening on the opposite side of said oven through which the products of combustion escape from said oven after traveling 35 the length of the oven, a flue extending downwardly on said opposite side of the oven and under the oven through which said products of combustion travel after leaving said oven, the bottom of the oven being left 40 above and below free from obstructions.

45 13. In a combined coal and gas range the combination of an oven having a coal grate and a gas combustion chamber on one side thereof separated from each other and located outside of said oven and at one and the same side of the oven and both operating to first heat said side of the oven, a flue for the coal grate arranged over the top and down the opposite side of the oven, 50 the oven being connected with the gas combustion chamber to permit the products of combustion of the gas chamber to pass across or through the oven itself and into said flue on the opposite side of the oven and a common flue arranged under the oven and up the back of the oven, said flue heating the same bottom whether coal or gas is burned separately or in combination.

55 14. In a combined coal and gas range the combination of an oven having a coal grate and a gas combustion chamber on one side thereof separated from each other and located outside of said oven and at one and the same side of the oven and both operating 60 to first heat said side of the oven, a

flue for the coal grate arranged over the top and down the opposite side of the oven, the oven being connected with the gas combustion chamber to permit the products of combustion of the gas chamber to pass across 70 or through the oven itself and into said flue on the opposite side of the oven and a common flue arranged under the oven and up the back of the oven, said flue heating the same bottom whether coal or gas is burned 75 separately or in combination, said bottom being the only bottom in said oven.

15. In a stove the combination of an oven, a grate for heating said oven, a gas burner located at the corner of the oven below said 80 grate, the products of combustion from said burner passing into the oven, said burner and grate being separated from each other, a flue extending around the outside of said oven through which the products of combustion from the grate pass, an opening 85 through one of the sides of said oven communicating with said flue, the products of combustion from said burner passing into the oven to said opening and then out of 90 the oven into the flue and passing through the flue under the bottom of the oven and up the flue back of the oven, said oven having but a single bottom.

16. In a stove the combination of an oven, 95 a gas burner and a coal grate for heating said oven, a flue extending around the outside of said oven through which the products of combustion from the grate pass, said burner being located at the side of the oven 100 parallel to said grate, an opening through one of the sides of said oven communicating with said flue, the products of combustion from the burner being discharged into the oven and passing out of the oven through 105 said opening into the flue and then passing through the flue under the bottom of the oven and up the flue back of the oven, said oven having but a single bottom.

17. In a stove the combination of an oven, 110 a gas burner and a coal grate for heating said oven, a flue extending around the outside of said oven through which the products of combustion from the grate pass, said burner being located at the side of the oven 115 parallel to said grate, an opening through one of the sides of said oven communicating with said flue, the products of combustion from the burner being discharged into the oven and passing out of the oven through 120 said opening into the flue and then passing around the outside of the rest of the oven, said burner and grate operating either separately or together to heat said oven, the products of combustion therefrom being combined outside of the oven and passed through the flue directly under the bottom and up the back of the oven, said oven having but a single bottom.

18. In a two fuel range having usual 130

top end and bottom flues around the oven, the combination of a gas burner situated at one end of the oven and communicating with the oven at one end thereof, said oven 5 being provided with an exit for the products of the gas combustion at the opposite end thereof, said exit communicating with

the bottom flue of the oven at the inlet thereof.

In testimony whereof I affix my signature. 10
